CLAIM

The ornamental design for a monitoring camera, as shown and described.

DESCRIPTION

FIG. 1 is a top, front, left perspective view of a monitoring camera showing our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a bottom plan view thereof; and,

FIG. 7 is a top plan view thereof.

The even broken lines shown in the drawings are included for the purpose of illustrating portions of the monitoring camera that form no part of the claimed design.

1 Claim, 7 Drawing Sheets
